CLAIM

The ornamental design for a cupholder assembly, as shown and described.

DESCRIPTION

FIG. 1 is a perspective view of a cup holder assembly. FIG. 2 is a perspective view of the cup holder assembly, with the drinkware attachment shown separately for ease of illustration. The broken lines showing of the drinkware is truncated for ease of illustration.

FIG. 3 is a bottom perspective view of FIG. 2.

FIG. 4 is a bottom view of FIG. 2.

FIG. 5 is a side view of FIG. 2.

FIG. 6 is a perspective view of the cup holder assembly, with the base shown separately for ease of illustration.

FIG. 7 is a top view of FIG. 6.

FIG. 8 is a side view of FIG. 6; and,

FIG. 9 is another side view of FIG. 6, shown rotated 45-degrees in respect to FIG. 8.

The broken lines show environmental subject matter and form no part of the claimed design.

1 Claim, 3 Drawing Sheets
